UNITED STATES PATENT OFFICE.

GEORG ULLRICH, OF MAGDEBURG, GERMANY, ASSIGNOR TO FRIED. KRUPP GRUSON-WERK AKTIENGESELLSCHAFT, OF MAGDEBURG-BUCKAU, GERMANY.

PROCESS AND APPARATUS FOR THE WET-MAGNETIC SEPARATION OF ORES AND OTHER MIXTURES OF MATERIALS ON DRUM SEPARATORS.

Application filed August 1, 1924, Serial No. 729,610, and in Germany September 13, 1923.

The present invention concerns a method of wet magnetic separation of ores and other material by means of a drum separator, the material being discharged onto the upper 5 surface of the drum. The invention consists in continuously discharging water or other liquid upon the separating surface so as to form a continuously renewed relatively thick layer of liquid on which the material, 10 dry or wet, is discharged. The magnetic particles penetrate the layer of liquid under the influence of magnetic force and their own weight and easily reach the separating surface, while the non-magnetic particles 15 are restrained from penetrating the layer of liquid by the surface tension thereof. In this way a clean separation of the material is attained.

The feed of the liquid forming said film is 20 effected appropriately immediately in front of the spot where the material is charged.

Another feature of the invention is the idea of subjecting the material to a preliminary cleansing by means of a liquid jet 25 directed through it. The particles removed by this liquid no longer enter into the separating process and the bulk of the waste material from which the magnetic particles are to be separated is thus advantageously 30 reduced.

In the accompanying drawing

Fig. 1 is a sectional view of a separator, working according to the new process.

Fig. 2 shows a longitudinal section 35 through a part of the drum of said separator.

Fig. 3 shows a longitudinal section through parts of a further modified form of the drum.

Around a magnetic pole *a* rotates a drum *b* upon which ring-shaped auxiliary poles *c* are fixed in the usual manner. A pipe *d* squirts water or any other liquid continuously against the walls of the ring-shaped space *e* formed by the auxiliary poles *c* and drum-mantle *b* in such a way that a film of water, which is continuously renewed, is formed on said walls. The material to be separated is introduced to the auxiliary poles by a feeder *f* at a spot placed behind the jet *d* in the direction of the rotation of the drum. The liquid squirted against the side walls of space *e* rises over the upper auxiliary poles in such a way that upon their

outer cylindrical surfaces a film of liquid is 55 likewise formed. The form of the section of the auxiliary pole rings may be such as drawn or any other whatsoever. There may be arranged between feeder *f* and the attracting auxiliary pole edges a second water 60 jet *g* which squirts transversely through the dropping stream of the crude material effecting thereby a cleansing of the raw material.

In the apparatus shown in Figure 3 no auxiliary poles are fixed on the drum *b*. 65 Here the ring-shaped separating space *e* is formed by annular rings *i* fixed on the drum *b*. The introduction of the liquid forming the film can be effected in the manner shown in the first described embodiment, or in any 70 other suitable way, the manner in which it is introduced being immaterial to the invention.

The process is applicable both for fine and 75 for coarse material.

What I claim is:

1. In a wet magnetic separator comprising a rotating separator element having an outwardly open circumferential channel, means for delivering a fluid to the side walls of 80 said channel for forming a film thereon, feeding means above said channel for the material to be separated and a liquid jet directed transversely through the material as it falls from said feeding means to the separator element. 85

2. In a wet magnetic separator comprising a rotating separator element having an outwardly open circumferential channel, means for delivering a fluid at the base of 90 the side walls of said channel for forming a film thereon, and means for feeding the material to be separated onto said film as and for the purpose described.

3. In a process of wet separation by means 95 of a magnetic separator, the step of directing a liquid jet through the material to be separated prior to the delivery of the material to the magnetic separator whereby particles carried along by said jet are removed from the action of the magnetic separator. 100

4. In a wet magnetic separator, a rotating annular pole having an exposed lateral surface, means for delivering a fluid to said 105 lateral surface for forming a film thereon, and means for delivering material to be separated adjacent said film.

5. In a wet magnetic separator, a rotating annular pole having an exposed lateral surface, means for delivering a fluid to said lateral surface at the inward extremity
5 thereof for forming a film thereon, and means for delivering material to be separated adjacent said film.

6. The process of wet magnetic separation of ores and other mixtures of materials by
10 the aid of a magnetic drum separator which consists in forming and continuously re-

newing a liquid layer on the upper surface of the drum, and then charging the material to be separated onto the liquid layer, whereby the magnetic particles penetrate by gravity and magnetic attraction to the surface of the drum, while the non-magnetic particles are restrained by surface tension. 15

In testimony whereof the foregoing specification is signed.

GEORG ULLRICH.
